UNITED STATES PATENT OFFICE.

MORRIS FRIEDMAN, OF CHICAGO, ILLINOIS.

DESIGN FOR A SHOW-CASE.

42,106.

Specification for Design.

Patented Jan. 23, 1912.

Application filed October 6, 1909. Serial No. 521,428. Term of patent 7 years.

To all whom it may concern:

Be it known that I, MORRIS FRIEDMAN, a citizen of the United States, residing at Chicago, in the county of Cook and State of Illinois, have invented a new, original, and ornamental Design for Show-Cases, of which the following is a specification, reference being had to the accompanying drawing, forming part thereof.

The drawing is a perspective of a show-case, embodying the new design.

The show-case is characterized in having a low front *a*, a relatively higher back *b*, a horizontal cover-section *c*, and a back cover-section *d* extending upwardly and rearwardly from the back of the horizontal sec-

tion *c* to the top edge of the high back *b*, an acute angled corner being formed by the meeting edges of the back *b* and section *d*, and sides *e* having their rear portions extending upwardly from the front portions. Vertical partitions *f* extend through the lower portion of the case from front *a* to back *b* and have horizontal upper edges.

I claim:

The ornamental design for a show-case as shown and described.

MORRIS FRIEDMAN.
